CLAIM

The ornamental design for the combination collapsible baby bed and shoulder bag, as shown and described.

DESCRIPTION

FIG. 1 is a top perspective view of a combination collapsible baby bed and shoulder bag showing my new design;

FIG. 2 is a side elevational view thereof; and,
FIG. 3 is an opposite side and bottom perspective view thereof.

The broken-line depiction of the buckle element in the views is for illustrative purposes only and forms no part of the claimed design.
